UNITED STATES PATENT OFFICE.

OTTO WÜRSCHER, OF LEIPSIC, GERMANY.

DESIGN FOR A CIGAR-DEALER'S SIGN.

SPECIFICATION forming part of Design No. 37,486, dated July 11, 1905.

Application filed June 10, 1905. Serial No. 264,738. Term of patent 7 years.

To all whom it may concern:

Be it known that I, OTTO WÜRSCHER, a citizen of the Empire of Germany, residing at Leipsic, in the Kingdom of Saxony and Empire of Germany, have invented a new, original, and ornamental Design for Cigar-Dealers' Signs, of which the following is a specification, reference being had to the accompanying drawing, forming a part thereof.

The figure is a side elevation of a cigar-dealer's sign, showing my new design.

I claim—

The ornamental design for a cigar-dealer's sign, as shown.

OTTO WÜRSCHER.
